AUTOMOBILE OR SIMILAR ARTICLE

Dallas R. Lamont, New York, N. Y.

Application July 18, 1955, Serial No. 37,021

Term of patent 14 years

(Cl. D14—3)

Fig. 1.

Figure 1 is a perspective view of an automobile or similar article embodying the novel design of the present invention;

The automobile, per se, is shown in broken lines in the above figures, and the dominant feature of my design resides in the portions shown in solid lines.

I claim:

The ornamental design for an automobile or similar article, substantially as shown and described.
